NEEDLE HOLDER FOR A RELOOPING NEEDLE

Bedri Hussein Gostkowski, Geneva, Switzerland,
assignor to "Societe Vitos", Troyes, FranceApplication November 7, 1936, Serial No. 109,656
In Switzerland November 8, 1935

10 Claims. (Cl. 66—1.5)

This invention relates to a needle holder for a relooping needle operated by means of a flexible wire effecting a reciprocating movement which same transmits to the needle by means of at least 5 one elastic member.

In the needle holder according to the invention, the movable part thus drawn along has such a freedom of movement that the same can freely operate under the influence of its inertia although 10 same is extremely light.

The accompanying drawings show some embodiments of the invention given by way of example.

Fig. 1 is a partial elevation and partial section, showing the holder with two elastic members.

Fig. 2 is a section on the line II—II of Fig. 1.

Fig. 3 is a detail of the needle holder of Fig. 1.

Figs. 4 and 5 show in diagram two different positions of the members of a needle holder with 20 a single spring.

Figs. 6 and 7 show in diagram a needle holder similar to that of the Figs. 4 and 5, but in which the action of the spring can be momentarily 25 annulled.

Fig. 8 is a partial longitudinal section of a needle holder constructed according to the diagrams of Figs. 6 and 7 and shows the means whereby the action of the spring may be annulled.

Fig. 9 is a detail on a larger scale of a part of 30 said means.

Fig. 10 is a view similar to Fig. 1, but on a larger scale of a needle holder with a single spring of gradually variable tension.

Fig. 11 is a section on the line XI—XI of Fig. 10.

The needle holder shown in Figs. 1 to 3 consists of a flanged sleeve 1 the end of which opposite a bottom 2 is obturated by a stopper made of two parts 3, 4 held together by means of the screws 40 5, the part 3 being adapted to rotate with regard to the part 4 integral with the sleeve 1. Two rods 6 integral with the part 4, extend parallelly along and inside the sleeve and are immobilized at their free ends by the bottom 2. A tube 7

45 fixed to the part 3, guides a flexible wire 8 intended to transmit a reciprocating movement to the relooping needle 9.

Said needle is fixed to a rod 10, integral with a cylinder 11 which is adapted to slide axially along 50 the rods 6, and which is guided on the one hand by the fact that some flanges 12 are in contact with said rods, on the other by the fact that the rod 10 passes through the opening in the bottom 2. Said guiding which engages only extremely

55 small surfaces offers practically no resistance to

the free movement of the movable part formed by the cylinder 11, the rod 10 and the needle 9.

The end of the cylinder opposite the needle is closed by a stopper 13 traversed by the flexible wire 8, the end of which is connected to a piston 14. Finally, said piston is engaged between two springs 15, 16 enclosed in the cylinder 11.

By means of any device, but preferably by means of the apparatus described in the patent application Ser. No. 109,657, filed Nov. 7, 1936, 10 simultaneously filed and copending herewith, entitled "Apparatus for operating a relooping needle", a rapid reciprocating movement is given to the flexible wire 8 relatively to the tube 1, a movement which is consequently also executed by the 15 piston 14 by compressing now one, now the other of the two springs 15, 16. The energy received is in its turn transmitted to the movable part.

The practically complete liberty of movement of said movable part will, under the influence of 20 the impulses received, make same move by virtue of its inertia and in both directions beyond the amplitude of the movement executed by the piston. The amplitude obtained depends in fact on said inertia and there is needed but a very 25 slight variation in the mass of the movable part to modify said amplitude, which also varies, automatically with the speed, same being greater at the high than at the low speeds, and also immediately diminishing if the fabric under work 30 offers unaccustomed resistance.

Wherefore, the work effected by the needle is effected by means of the energy stored and returned by the movable part, independently of the power of the motor used to drive the flexible wire. 35 Now, as said movable part is extremely light, that is to say of a weight round about two grams, the slightest resistance slows down same without any effort and the stitches cannot be torn.

To give the maximum liberty possible to the 40 movable part, by diminishing all the friction, the piston 14 could be shaped as shown at 14' in Fig. 3, in which the circle 11' represents the inside wall of the cylinder 11.

It is further necessary that it should be possible 45 for such a needle holder to be held very lightly, without same however vibrating under the rapid movements of the movable part. To this end, the sleeve 1 passes, at least partially, through a spherical body 17, which is easily gripped and 50 presenting, although made of light material, a mass which is relatively great with regard to that of the movable part. Said spherical body can be made of cork, rubber, fibre, ebony, wood, etc.

Instead of effecting the elastic transmission by 55

means of two springs, it is also possible to effect same by means of a single spring, as shown in Figs. 4 and 5. The advantage realized is that of being able to diminish the length and, consequently, the weight of the movable part, while yet having an elastic transmission having all the flexibility required for working on finer materials.

In this case, the sleeve of the needle holder is designated by 18 and the movable cylinder in side said sleeve by 19. Said cylinder is extended in a pipe 20 carrying the needle 21. To the flexible wire 22 are fixed two abutments 23, 24, the second of which is guided by the pipe 20. Between said abutments the two washers 25, 26 enclosed in the cylinder 19 are engaged and between said washers is located the single spring 27.

When the flexible wire 22 effects its reciprocating movement, this is what happens:

As the flexible wire is drawn along in the direction of the arrow 28 of Fig. 1, the abutment 24 draws along the washer 26 and compresses the spring 27 against the washer 25, which is held back by the cylinder 19, to which said washer transmits the impulse received. The cylinder 25 with the needle rises in the direction of the arrow 28.

As the flexible wire is then pushed back in the direction of the arrow 29 of Fig. 5, it is the abutment 23 that meets in its turn the washer 25, which compresses the spring against the washer 26, likewise held back by the cylinder to which same transmits the impulse received. The cylinder with the needle is lowered in the direction of the arrow 29.

For certain kinds of work, it may be useful, while yet disposing of an extremely adaptable mechanism as the one just described, to annul therefrom momentarily the adaptability in order to reloop a coarser material.

Figs. 6 and 7 show how the embodiment of the needle holder of Figs. 4 and 5 can be modified so that it may be possible to work at will either with the elastic connection or without any elastic connection. The construction shown is similar to that of Figs. 4 and 5, but the abutment 24 sliding in the pipe 20, comprises a circular groove 30 into which the pins 31 can be introduced. In the position of said pins according to Fig. 6, the abutment 24 is adapted to slide freely in the pipe 20 and the needle holder works exactly as described with reference to Figs. 4 and 5. In the introduced position of said pins, according to Fig. 7, the abutment 24 becomes integral with the pipe 20 and consequently it can be said that the flexible wire 22 and the pipe 20 make but one piece. The needle is then forced to follow exactly the displacements of the flexible wire, without any elastic member being placed between them.

The working of the pins 31 can be realized in practice, as shown in Fig. 8, in which the sleeve 18, the cylinder 19, the pipe 20, the abutment 24, the washer 25 and a portion of the needle 21 are seen once again.

The pipe 20 carries the ears 32 guiding a clip 33 which is accessible from the outside at 34 and which is capable of acting on the pins 31 by means of its curved, bent ends 35. In the position shown in Fig. 8, the pins 31 penetrate into the groove 30 of the abutment 24 and the elastic effect is suppressed. By making the clip 33 slide in the direction of the arrow 36, the abutment 24 is freed from the action of the pins 31, because same, as shown in Fig. 9, are subjected to the

action of the small springs 37. At that moment, the elastic transmission is reestablished.

Finally Figs. 10 and 11 show how instead of letting the elastic transmission act or of suppressing same completely, said elastic transmission may within broad limits be made adjustable, so that it may be adapted approximately to the quality of fabric that is being relooped.

Said embodiment consists of the same elements as the preceding embodiments and is of the type 10 acting with one spring and working therefore in the way described with reference to Figs. 4 and 5.

The flexible wire arrives at 38 through the tube 39, passes through the stopper made of the two pieces 40, 41, the portion 40 of which is adapted 15 to turn in the portion 41, with which the sleeve 42 engaged in the spherical body 43 is integral. In said sleeve extend longitudinally the two guides 44 for the cylinder 45 inside of which is located the spring 46. Said spring is confined between 20 the washers 47 and 48, the washer 48 forming a nut as regards the threaded portion 49 of a tube 50 carrying a thumb wheel 51.

The flexible wire acts on the washer 47 and on the tube 50 by means of the abutments 52 and 53, with interposition of the small springs 54 to 25 deaden the shocks.

Between the sleeve 42 and the tube 50 is located another tube 55 extending in the cylinder 45 and serving for fixing the needle 56 by means of a 30 tightening device 57.

Finally the sleeve 42 and the tube 55 are open at 58 and 59 to permit access to the thumb wheel 51 and to make same rotate as well as the tube 50, while the washer 48 is angularly immobilized 35 by the guide pins 60 guiding same radially in the grooves 61 of the cylinder 45.

The working of the needle holder is identical with that represented in Figs. 4 and 5. The spring 46 acts on the upper portion of the cylinder 40 45 by means of the washer 47 and on the lower portion by means of the washer 48 and of the edge 62 of the tube 50. The flexible wire acts on the other hand, on the upper part, by means of the abutment 52 and on the lower part 45 by means of the abutment 53 and of the tube 50.

It is however to be remarked that by making the tube 50 rotate, the washer 48 can be moved axially and thus diminish the free distance existing between same and the washer 47, and this increases the tension of the spring 46. It is due to this, that it is possible to adjust the tension of the spring: the needle holder works as if it possessed an interchangeable spring, that is to say capable of being replaced, at will, by other springs 55 of different force. The small spring 63 serves to deaden the eventual shocks between the washer 47 and the upper end of the threaded portion 49 of the tube 50.

What I claim is:—

1. In a needle holder for a relooping needle having a movable needle holder part adapted to receive the needle and be operated by a flexible wire effecting a reciprocating movement which the same transmits to the needle by means of at 65 least one elastic member, the combination of unaltered non-clamping guide means for guiding the movable part of the needle holder causing said needle holder part thus drawn along to have such a freedom of movement that said movable 70 part can be subjected during operation to the influence of its inertia.

2. A needle holder for a relooping needle operated by a flexible wire effecting a reciprocating movement which same transmits to the nee- 75

- dle by means of at least one elastic member, the movable part of the needle holder thus drawn along having such a liberty of movement that said movable part can be submitted to the influence of its inertia and a member containing the movable part passing at least partly through a spherical body permitting of gripping the holder and presenting a relatively big mass with regard to that of the movable part.
- 5 3. A needle holder for a relooping needle operated by a flexible wire effecting a reciprocating movement which same transmits to the needle by means of at least one elastic member, the movable part of the needle holder thus drawn along having such a liberty of movement that said movable part can be submitted to the influence of its inertia and a spring surrounding the end of the flexible wire being located in a cylinder and between two abutments of the flexible wire, against which same bears by means of washers enclosed in the cylinder, in which said washers can slide and into which the abutments can penetrate, said cylinder forming the chief portion of the movable part.
- 10 4. A needle holder for a relooping needle operated by a flexible wire effecting a reciprocating movement which same transmits to the needle by means of at least one elastic member, the movable part of the needle holder thus drawn along having such a liberty of movement that said movable part can be submitted to the influence of its inertia and a spring surrounding the end of the flexible wire being located in a cylinder and between two abutments of the flexible wire, against which same bears by means of washers enclosed in the cylinder, in which said washers can slide and into which the abutments can penetrate, said cylinder forming the chief portion of the movable part, the washers being polygonal so as to touch the wall of the cylinder only by points.
- 15 5. A needle holder for a relooping needle operated by a flexible wire effecting a reciprocating movement which same transmits to the needle by means of at least one elastic member, the movable part of the needle holder thus drawn along having such a liberty of movement that said movable part can be submitted to the influence of its inertia and a spring surrounding the end of the flexible wire being located in a cylinder and between two abutments of the flexible wire, against which same bears by means of washers enclosed in the cylinder, in which said washers can slide and into which the abutments can penetrate, said cylinder forming the chief portion of the movable part, the cylinder having a tubular extension of its end bearing the needle and in which is guided longitudinally a prismatic member forming one of the abutments.
- 20 6. In a needle holder for a relooping needle having a movable needle holder part adapted to receive the needle and be operated by a flexible wire effecting a reciprocating movement which same transmits to the needle by means of at least one elastic member, the combination of unaltered non-clamping guide means for guiding the movable part of the needle holder causing said needle holder part thus drawn along to have such a freedom of movement that said movable part can be subjected during operation to the influence of its inertia, means being provided to permit of modifying the deadening effect produced by the elastic member drawing along the movable part.
- 25 7. A needle holder for a relooping needle operated by a flexible wire effecting a reciprocating movement which same transmits to the needle by means of at least one elastic member, the movable part of the needle holder thus drawn along having such a liberty of movement that said movable part can be submitted to the influence of its inertia, bolting means being provided by means of which the movable part can be firmly connected to the flexible wire.
- 30 8. A needle holder for a relooping needle operated by a flexible wire effecting a reciprocating movement which same transmits to the needle by means of at least one elastic member, the movable part of the needle holder thus drawn along having such a liberty of movement that said movable part can be submitted to the influence of its inertia, guide pins being provided which can be made to penetrate into a part to be bolted in order that the movable part can be firmly connected to the flexible wire.
- 35 9. In a needle holder for a relooping needle having a movable needle holder part adapted to receive the needle and be operated by a flexible wire effecting a reciprocating movement which same transmits to the needle by means of at least one elastic member, the combination of unaltered non-clamping guide means for guiding the movable part of the needle holder causing said needle holder part thus drawn along to have such a freedom of movement that said movable part can be subjected during operation to the influence of its inertia and the space occupied by the elastic member being of variable length, so that said member is more or less compressed therein.
- 40 10. In a needle holder for a relooping needle having a movable needle holder part adapted to receive the needle and be operated by a flexible wire effecting a reciprocating movement which same transmits to the needle by means of at least one elastic member, the combination of unaltered non-clamping guide means for guiding the movable part of the needle holder causing said needle holder part thus drawn along to have such a freedom of movement that said movable part can be subjected during operation to the influence of its inertia, the holder being provided with a rotative member of the movable part, which is accessible from the outside and carries a screw thread and a circular nut, possible for said circular nut being displaceable by the rotation of the rotative member, so as more or less to compress the elastic member.

BEDRI HUSSEIN GOSTKOWSKI.
